UNITED STATES PATENT OFFICE.

CARL ENKE, OF NUERMBERG, BAVARIA, ASSIGNOR TO VICTOR HENRY
VON SWAINE, OF WIESBADEN, GERMANY.

ROTARY ENGINE.

SPECIFICATION forming part of Letters Patent No. 297,589, dated April 29, 1884.

Application filed January 9, 1884. (No model.) Patented in Germany May 7, 1882, No. 22,356.

To all whom it may concern:

Be it known that I, CARL ENKE, of the city of Nuremberg, in the Kingdom of Bavaria, German Empire, have invented an Improvement in Rotary Engines; and I do hereby declare that the following specification is a full description of the same, reference being had to the accompanying drawings, forming part of this specification.

- 10 Similar letters of reference indicate corresponding parts in the several figures.
Figure 1 is an elevation of the machine, partly in section. Fig. 2 is a plan. Fig. 3 is a vertical section of the cylinder. Fig. 4 is an 15 inside view of the cylinder; Fig. 5, an outside view. Fig. 6 is a vertical section of the two piston-wheels, of which Fig. 13 shows one in a view. Figs. 7, 8, 9 show one piston-wheel in section and elevation, and a plan of two such 20 wheels at the point of their narrowest gearing. Figs. 10, 11, 12 represent a piston-wheel in a plan view, and two such wheels at the point of their narrowest and widest position.

To facilitate the understanding of the invention, imagine two bevel-gears—the shafts or axis of which form a very obtuse angle—with very coarse and long teeth inclosed in a casing in such manner that every empty space not necessary for the rotary motion of the two gears 25 is filled up or avoided, and steam admitted at one side of the contact-point of the two pitch-lines, leaves the casing at the other side of this point. Then the steam will have pressed upon the same sides of the teeth of the gears 30 and forced the latter to rotate. This idea explains the character of the machine to which 35 my invention is applied.

The invention consists in the novel combination of parts hereinafter more clearly pointed 40 out and claimed.

Upon the shaft $e e'$ are mounted two bevel-gears, $a a'$, the teeth of which, $t t'$, Figs. 6 and 45 13, are gearing at the lower side of these figures. As gear-teeth in their propel and correct form would not be practicable for the object they have to perform in the present case, each of the teeth $t t'$ is radially extended, so as to 50 form paddles or pistons $b b'$, which, not having the exactly correct form of teeth, nevertheless near each other closely enough at the

point of gearing, so as to hinder at this point an improper escape of steam or fluid; or the ends of these pistons may possess the correct form of teeth, Figs. 10, 11, 12, in which case they are provided with passages p , to facilitate 55 the entrance of steam (or water) at the lower point of gearing, where the teeth come in close contact, as shown in Fig. 11, while in Fig. 12 is represented the position of the pistons $b b'$ in their top position. The shafts $e e'$ form with 60 each other an obtuse angle and the small space between the gears $a a'$ and the teeth and pistons $t b t' b'$ is as much as possible filled up by a casting or filler, d , suitably shaped, with a tail-piece, d' , Fig. 6. These shafts turn in suitable 65 bearings, and the gears, with their pistons, are inclosed into a corresponding casing, which, made in two parts, receives and secures the tail-piece d' .

Instead of attaching the pistons $b b'$ directly 70 to the teeth $t t'$ and in one casting, they may be made separate from them.

Figs. 1, 7, 8, and 9 show the pistons $b b'$ attached to the rim of the disks $g g'$, mounted to the shafts $e e'$, which carry also the bevel-gears 75 $a a'$. The filler d is fitted steam-tight to recesses of the disks $g g'$ incasing the gears $a a'$, and fastened by its tail-piece d' between the crooked flanges of the two halves $c c'$ of the engine case or cylinder. (See also Fig. 4.) 80 The cylinder $c c'$ is provided at its centers with bearings and stuffing-boxes for the shafts $e e'$, and mounted to foundation-plate, which supports also two further pillow-blocks for the shafts $e e'$. The cylinder $c c'$ is provided also 85 with two short flanged pipes, $f f'$, for the admission and the exhaust of the steam, or for the suction and the forcing of fluids if the design is used as a pump, in which case power is applied at one of the shafts $e e'$, as shown in 90 Figs. 1, 2. The cylinder $c c'$ may be constructed in another way, as shown in Figs. 14, 15. The conical parts are made without crooked flanges, but form two uniform heads, $c c'$, while the filler d is cast in one piece with the upper part 95 of the cylindrically-shaped case or ring $d' d'$, the lower part of which is screwed to the upper one. To the recessed flanges of this ring the two heads $c c'$ are screwed or otherwise jointed. In these figures is shown also that 100

the bevel-gearing $a a'$ may be dispensed with and replaced by the well-known universal joint.

It must be remarked that the machine may 5 be used as motor and driven by steam, water, or the like; or that it may be used as pump, blower, water-wheel, &c. Which of the pipes $f f'$ will be the inlet or suction and which the outlet depends wholly from the direction in 10 which the piston-wheels rotate. By changing this direction the office of the pipes f and f' is reversed.

I lay no claim to anything that is shown and disclosed in Letters Patent of the United 15 States No. 32,372.

I claim—

1. A rotary engine consisting of the case c

c' , beveled-gear wheels $a a'$, mounted upon shafts $e e'$, the said gear-wheels being connected with the paddles $b b'$, of the filler $d d'$, and of inlet and outlet pipes $f f'$, all combined and arranged substantially as herein shown and described.

2. In rotary engines, the case $c c'$, made in two parts, that are so arranged as to form the 25 flanged pipes $f f'$, in combination with the filler d , having tail-piece d' , substantially as shown and described.

This specification signed by me this 2d day of October, 1883.

CARL ENKE.
